UNITED STATES PATENT OFFICE.

EDWARD FOOSE, OF WASHINGTON, DISTRICT OF COLUMBIA.

METAL CABINET.

Application filed May 15, 1923, Serial No. 639,190. Renewed March 4, 1926.

This invention relates to an improvement in metal cabinets.

The principal object of this invention is the provision of an improved construction and arrangement of lockers which will provide the necessary locker equipment for a given number of users through the utilization of a minimum of floor space, and reduce the cost of locker installation. I attain this object by a certain arrangement of parts in a locker whereby a high narrow space is provided for the hanging of garments and other articles requiring more room in height than in width, and a wider space but relatively low in height for the storage of hats and other articles that require a wider space than that provided for garments. In lockers as generally built there is about twice as much space than is necessary for garments if this space is made as wide as the space provided for hats. By constructing lockers embodying my invention with a wide space at the top and at the bottom, the intermediate spaces being of less width, manifestly, there is a considerable saving of space without reducing the usefulness of the locker.

A further object of my invention is the provision in a double deck locker of means that may be used as a step in the lower locker and as a hand-hold in the upper locker to enable the user to reach to the upper part of a double deck locker. Lockers of this type are generally, or preferably, built relatively low in height. This means will permit the construction of a higher locker, and adapt the double deck locker to children without their using benches or other means to reach to the top of the upper locker.

This invention consists of certain novel features of construction and combination of parts which will be described and set forth in the accompanying drawings.

In the drawings—

Figure 1, is a front elevation of a double locker with the doors closed;

Figure 2 is a front elevation of a double locker with the doors open;

Figure 3 is a horizontal section on the line 3—3 of Figure 4;

Figure 4 is a front elevation of a pair of double deck lockers;

Figure 5 is a vertical section on the line 5—5 of Figure 4;

Figure 6 is a developed side elevation of

the locker partition member shown in Figure 7;

Figure 7 is a front elevation of the partition member of the locker illustrated in Figure 2;

Figure 8 is a front elevation of the partition member of the locker illustrated in Figure 4;

Figure 9 is a developed side elevation of the locker partition member shown in Figure 8;

Figure 10 is a horizontal section of part of a multiple locker structure with partition members similar to the partition illustrated in Figure 2;

Figure 11 is a front elevation of a cabinet structure with multiple compartments; and

Figure 12 is a vertical section on line 12—12 of Figure 11.

The principal feature of my invention is a novel partition member in a rectangular oblong compartment of a locker or cabinet body, dividing said compartment into two compartments, each of said compartments adapted for receiving garments, hats and other articles. Both the locker or cabinet body and the partition member are built preferably of sheet metal.

In Figures 1, 2, 6 and 7 is shown a preferred embodiment of my invention applied to single tier lockers. The locker body having sides 1, back 2, top 3 and a bottom 4, and may be of any usual or special construction with such reinforcing members as may be desired.

The partition member 5, dividing the locker or cabinet into compartments 6 and 7, comprises a shelf 8, a vertical partition 9, a horizontal partition 10, upper closure wall 11, lower closure wall 12, side flanges 13, back flanges 14 and 15, front flange 16, and bottom flange 17. This partition member 5 is preferably made of one piece of sheet metal, though not necessarily so, as various parts can be made separately and welded together, or made separately with additional flanges to those shown, and spot welded, riveted or bolted together.

If made of one piece the parts are all bent at a right angle to each other along dotted lines indicated in Figure 6, and in the various directions necessary to form the fully shaped partition member 5 of which a front elevation is shown in Figure 7. Shelf 8 is bent to the left of vertical partition 9, up-

per closure wall 11 is bent upward from shelf 8, horizontal partition 10 is bent to the right of vertical partition 9, and lower closure wall 12 is bent downward from horizontal partition 10. This shaped partition member 5 with the flanges properly bent is secured to body of locker by spot welding, or otherwise securing side flanges 13 to sides 1, back flanges 14 and 15 to back 2, front 10 flange 16 to bar 18, and bottom flange 17 to bottom 4. The bar 18 should be preferably the same thickness as frame pieces 19 and 20 to which it is secured by welding or otherwise. Ends of closure walls 11 and 15 12 in contact with back of bar 18 and in contact with back of frame pieces 19 and 20 to which it is secured by welding or otherwise. Ends of closure walls 11 and 12 in contact with back of bar 18 and in contact 20 with back of frame pieces 19, 21 and 22 are secured to same by spot welding or otherwise. The bar 18 forms a stile for doors 23 and 24 to strike against, and to which door 25 is hinged (Figure 10).

It is evident that when the partition member 5 is thus installed there are not only two compartments 6 and 7, but each compartment has a recessed part which I will designate as recess 26 of compartment 30 7 and recess 27 of compartment 6.

From the foregoing description and illustrations referred to it is manifest that recess 26 is accessible only from compartment 7 when door 24 is open and is really a part thereof; while recess 27 is accessible only from compartment 6 when door 23 is open, being likewise, substantially a part thereof.

In Figure 4 a preferred embodiment of a two tier, or double deck, locker is disclosed. In these lockers, I have shown a modified form of the partition member illustrated in Figure 2. In a two tier locker it is manifestly necessary to keep the height as low as is consistent with the use to which the locker is to be put. If an overcoat is the longest garment that will likely be put in the locker, it need not be much higher than the length of the overcoat if space is provided on the side for a hat and other articles. Space for a hat is provided in the recess described herebelow and space for coats and other short garments is provided for on the wall below the recess. With this arrangement two locker compartments can be provided for each tier of a double decker with a small fraction of additional space to that required for one as usually built heretofore.

The partition member 28 partitioning off compartment 29 from compartment 30 comprises an upper vertical partition 31, a shelf 32, a middle vertical partition 33, a horizontal partition 34, a lower vertical partition 35, upper closure wall 36, lower closure wall 37,

back flanges 38, 39 and 40, top flange 41, front flange 42, and bottom flanges 43 and 44. This partition member 28 like partition member 5 described herebefore is preferably made of one piece of sheet metal.

If made of one piece, the parts are all bent at a right angle to each other along dotted lines indicated in Figure 9 and in the various directions necessary to form the fully shaped partition member of which a front elevation is shown in Figure 8. The shelf 32 is bent to the left of middle vertical partition 33, upper vertical partition 31 is bent upwards from shelf 32, upper closure wall 36 is bent inwardly from upper vertical partition 31 and welded along its bottom edge to front edge to shelf 32, horizontal partition 34 is bent to the right of middle vertical partition 33, lower vertical partition 35 is bent downwards from horizontal partition 34, lower closure wall 37 is bent inwardly from lower vertical partition 35 and welded along its top edge to front edge of horizontal partition 34. This shaped partition member 28 with the flanges properly bent is secured to body of locker by spot welding, or otherwise securing back flanges 38, 39, and 40 to back 45, top flange 41 to horizontal partition 46, bottom flanges 43 and 44 to bottom of locker 47, front flange 42 to bar 48. This bar 48 should be preferably the same thickness as frame 49 to which it is secured by welding or otherwise. Ends of closure walls 36 and 37 in contact with back of bar 48 and top end of closure wall 36 in contact with back of frame 49 are secured to same by spot welding or otherwise.

From the foregoing description it will be evident that a recess 50 is formed back from vertical partition 33 enclosed by shelf 32, upper vertical partition 31, closure wall 36, part of back wall 45, and part of horizontal partition 46, which recess is accessible only from compartment 30 when door 54 is open, and is really part of compartment 30. A similar recess 51 is accessible from and forms part of compartments 29.

My invention is applicable not only to the type of locker illustrated in Figures 1, 2, 3 and 4 which is substantially a single locker unit converted into a double one, but also to locker structures consisting substantially of a plurality of oblong rectangular compartments each of which can be converted into two locker compartments. In a structure of this kind it would be desirable to swing all doors in one direction thereby using bar 18 on partition member 5 as a stile to hinge doors 25 to, as well as a strike for doors.

My invention is applicable also to cabinets without doors, a preferred embodiment of which is illustrated in Figures 11 and 12. This structure is built preferably of sheet

metal comprising a body with back 55, base 56, horizontal partition 57, top 58, all vertical partitions 59, partition members 60, garment hooks 61 and hat hooks 62. All parts of this structure are preferably connected with each other by flanges and may be secured to one another by spot welding or otherwise. Partition member 60 would be made substantially like partition member 5 shown in Figures 6 and 7 except that closure walls 11 and 12 and flanges 16 and 17 would be omitted, and other parts proportioned and shaped to fit the cabinet structure referred to.

It is manifest from the illustrations and the foregoing description that these cabinet compartments may be made narrow and yet provide ample space for garments and hat because of the novel arrangement. A cabinet of this type would be useful in some schools and other places where locker equipment is not needed. It would provide an inexpensive compact structure to replace the usual wall hooks and shelf in use in many places.

The step and hand hold device illustrated in Figures 3, 4, and 5 is a preferred embodiment of this invention and consists of a rod of metal bent so that the step and hand-hold part 63 is slightly above the horizontal partition 34 extending upward at a right angle and secured to vertical partition 33, and bent downward at a right angle to the bottom 47 of the locker, at which point it is bent outwardly at a right angle and secured to bottom 47 or to horizontal partition 46. This step and hand hold member 63 also functions as a brace for partition 33 and thus serves to stiffen the locker structure. An opening 64 in doors is required for insertion of foot in lower locker and hand in upper locker. This opening 64 may have a curved cover 65 at the back of opening and above rod 63, said cover being spot welded or secured otherwise to door. It is understood that step and hand-hold part may be integral with horizontal partition 34 or may be secured in place below said horizontal partition at a suitable distance instead of above it. It may also be a device fastened only to horizontal partition 34 instead of to vertical partition 33 and bottom 47.

A modification of step and hand-hold device is shown in Figures 11 and 12 in which a metal rod 66 is run horizontally along the front of cabinet and held in place by brackets 67, end of rod may have knobs 68 or other means to prevent it from sliding out of brackets 67.

Having described my invention what I claim is:

1. A double locker unit comprising back, side and top and bottom walls, doors each covering one lateral half of the front of said unit, a partition between the lateral

halves of said unit consisting of a vertical web extending from front to back of the unit and terminating in spaced relation to the top and bottom walls of the unit, and a compartment in each unit closed at its front and opening into the other unit, the bottom of one compartment extending from the top of the partition, and the top of the other compartment extending from the bottom of the partition.

2. A double locker unit comprising back, side and top and bottom walls, doors each covering one lateral half of the front of said unit, a partition between the lateral halves of said unit consisting of a vertical web extending from front to back of the unit and terminating in spaced relation to the top and bottom walls of the unit, and a compartment in each unit closed at its front and opening into the other unit, the bottom of one compartment extending from the top of the partition, and the top of the other compartment extending from the bottom of the partition, said compartment top and bottom extending entirely across the unit wherein the compartment is located.

3. A locker, comprising a body having doors, a partition dividing the body into two compartments, said partition being spaced from the top and from the bottom of the body, means associated with the partition at the ends thereof for forming recesses, and one recess extending into one compartment and the other recess extending into the other compartment, and a brace extending from one end of one compartment and engaging said partition, said brace forming a step or hand hold, and one of said doors having an opening therein to expose a portion of said brace when the door is closed.

4. A locker, comprising a body having doors, a partition dividing the body into two compartments, an L-shaped brace extending from one end of one compartment and engaging said partition, said brace forming a step or hand hold, and one of said doors having an opening therein to expose a portion of said brace when the door is closed.

5. A locker, comprising a body, a partition dividing the body into two compartments, a brace formed in one of said compartments and engaging said partition said brace having a horizontal portion serving as a step or hand hold.

6. A locker, comprising a body having doors, a partition dividing the body into two compartments, a brace formed in one of said compartments and engaging said partition, said brace having a hand or foot engaging portion, and one of said doors having an opening therein to permit access to said foot or hand engaging portion when the door is closed.
